**PRESET CONSOLE FOR A SERVICE STATION
OR THE LIKE**

Terry J. Simpkins, Dublin, Ohio, and George D. Robinson, Jr., Greensboro, N.C., assignors to Gilbert & Barker Manufacturing Company, New York, N.Y.

Filed Sept. 2, 1969, Ser. No. 18,941

Term of patent 14 years

Int. Cl. D20—99

U.S. Cl. D52—2

FIG. 1

FIG. 2

FIG. 3

FIG. 4

FIG. 1 is a front perspective view of a three unit modular preset console for a service station or the like embodying our design;

FIG. 2 is a front elevational view, somewhat reduced, of FIG. 1;

FIG. 3 is a right side elevational view of FIG. 2; and

FIG. 4 is a top plan view of FIG. 2.

The rear is essentially plain and unornamented as indicated by FIGS. 3 and 4.

We claim:

The ornamental design for a preset console for a service station or the like, as shown and described.
